US00D610417S

(12) **United States Design Patent**
Robinson et al.

(10) **Patent No.:** **US D610,417 S**
(45) **Date of Patent:** **** Feb. 23, 2010**

(54) **PLIERS**

(75) Inventors: **Glenn Robinson**, Coral Springs, FL (US); **Michael Garcia**, Oakland Park, FL (US)

(73) Assignee: **IBT Holdings, LLC**, Deerfield Beach, FL (US)

(**) Term: **14 Years**

(21) Appl. No.: **29/301,642**

(22) Filed: **Mar. 11, 2008**

(51) **LOC (9) Cl.** **08-05**

(52) **U.S. Cl.** **D8/52**

(58) **Field of Classification Search** D8/4, D8/14, 51, 52, 54–56, 58, 105, 107, 75–81; 7/125–137, 143–147; 81/300, 342, 348, 81/355–362, 364–366, 385–404, 407–418, 81/424.5, 426, 426.5, 427, 427.5

See application file for complete search history.
